UNITED STATES PATENT OFFICE.

ADELARD AMYOT, OF MONTREAL, QUEBEC, CANADA.

SHOW-CASE OR REFRIGERATOR.

1,257,300.

Specification of Letters Patent. **Patented Feb. 26, 1918.**

Application filed September 17, 1915. Serial No. 51,209.

To all whom it may concern:

Be it known that I, ADELARD AMYOT, a subject of the King of Great Britain, and residing at 590 Valois street, Montreal, Province of Quebec, Canada, have invented certain new and useful Improvements in Show-Cases or Refrigerators, and do hereby declare that the following is a full, clear, and exact description of the same.

10 This invention relates to cases for the reception and preservation by cooling of perishable commodities and an object of the invention is to provide an improved mode of ventilation for such cases.

15 Another object is to improve the construction of such cooling cases.

Another object is to provide an improved cooling case which may be used with or without ice.

20 Further objects and advantages will be hereinafter more fully described and particularly pointed out in the appended claims.

For full comprehension, however, of my invention, reference should be had to the accompanying drawings forming a part of this specification, in which similar reference characters indicate the same parts and wherein:

Figure 1 is a perspective view of the show 30 case employed with an ice-chest;

Fig. 2 is a similar view of the case without the ice-chest;

Fig. 3 is a horizontal section on line 3—3 Fig. 5;

Fig. 4 is an enlarged transverse section of the upper part of the showcase;

Fig. 5 is a longitudinal vertical section on line 5—5 Fig. 6;

Fig. 6 is a transverse vertical section on line 6—6 Fig. 5 and

Fig. 7 is a detail perspective illustrating the corner constructions with the parts disconnected.

While my invention is applicable to refrigerators I have illustrated it in connection with a show case which consists preferably of base 2, corner posts 33, 41, top frame 4, shelving 5 and rear doors 6, provision being made for the cooling of the case either 50 by ice or by the admission of cooled air, as will be presently described.

The front, ends and top of the cooler are double walled, the showcase having spaced sheets 7 and 8 of glass at the front and sides 55 and spaced sheets 9 and 10 of glass at the top and I have provided an improved means of

ventilation for the spaces between the inner and outer walls and the interior of the case which preferably consist of vents 11 extending from the interior to the exterior of the 60 case and vents 12 and 13 respectively extending from the spaces between the inner and outer walls to the exterior of the case.

In the preferred form the vents 12 extend substantially horizontally from the space 65 between walls 9 and 10 outwardly to the atmosphere through the top frame at suitable intervals around the latter and the vents 11 extend from the interior of the case diagonally upwardly through the top frame and 70 respectively communicate with one of the vents 12 between the ends of the latter while the vents 13 extend from the spaces between walls 7 and 8 upwardly through the top frame and respectively communicate with 75 one of the vents 12 between the ends of the latter and at the junction of vents 11 and 12. In this way a three-way vent is formed at the front and ends of the case and a two-way vent at the rear so that the ascending 80 heated or contaminated air in both the interior of the case and between the inner and outer walls is continuously carried off and the full efficiency of the cool air admitted to the case utilized for the preservation of 85 the contents of the latter, the disposal or elimination of heated air being accelerated by the union of the different vents in that the passage of air through one tends to create a suction in the other and so sucks the air there- 90 through.

Vertically spaced supports 14 for the shelves 5 extend transversely across the end of the case from front to rear corner posts to which they are secured by screws, the 95 shelves, which are spaced from the front and rear of the case to facilitate circulation, resting loosely upon and extending between these supports and additional supports 15 screwed to pairs of uprights 16 disposed 100 toward the center of the case those of said uprights at the rear extending between and being screwed at their ends to the base and rear portion of the top frame for which they constitute a brace to prevent sagging 105 thereof. The front uprights 16 are spaced from the inner front wall and are secured at the bottom to the base 2 by screws, the tops of such outer uprights being spaced from the top of the case and secured to the 110 uppermost supports 15 by mortising, the other supports 15 being notched to receive

the uprights and brace same against twisting. The lower ends of the uprights 16 are braced by pieces 17 screwed to the base and extending transversely of the case between the front and rear uprights of each pair and by pieces 17^a screwed to the base and extending between the front upright and front of the case, said pairs of uprights being spaced longitudinally of the case to provide a central space for the accommodation of an ice-chest 18.

There are preferably three doors 6 which are slidably mounted upon tracks 18^a and individually of less width than the case but adapted to collectively completely close the back of the case and may be moved to provide an opening giving access to either end of the showcase or as shown in Fig. 3 the space between the uprights 16 so that the ice chest may be inserted or removed.

When the ice-chest is inserted it rests loosely upon shoulders 19 presented by the braces 17 and is therefore spaced upwardly from base 2, the top of the chest being provided with a perforated cover 20 and the sides having apertures 21 in line with each shelf space, the base braces 17 having vents 22 extending therethrough from the central space beneath the chest to the opposite end spaces of the case so that with the ends of the shelves spaced from the front and back of the case, a thorough and complete circulation throughout the case is secured.

The front of the ice-chest is spaced from the inner front wall of the case, being preferably flush with the outer uprights 16 and the supports 15 extend outwardly from the chest and support smaller shelves 23 extending across the front of the chest, movement of the chest in a forward direction being limited by a stop 24 which rests loosely upon braces 17^a and constitutes a lower shelf which with the other shelves 5 and 23 can be removed.

45 A water outlet 25 from the chest through the base is provided but if it is desired to use the case without an ice-chest the latter may be removed, in which case the outlet 25 is plugged and chilled air admitted to the case through pipe 26 which may lead, from the outside of a building for instance to an opening 27 disposed about the center of base 2, and which is closed by a plug or cap 28 when the ice-chest is utilized.

55 When the case is thus cooled without the aid of ice the central space is filled in with shelves 29 upheld by the supports 15, the perforated cover 20 of the ice-chest being placed upon the shoulders 19 flush with stop 24 and while serving as a lower shelf also acts as a baffle for distributing the chilled air laterally through vents 22 as it enters through opening 27.

The several units of the showcase are 65 made of standard size for convenience of

renewal and are for the most part formed to strongly interlock and fastened in place by screws only so that the case can be readily taken apart and packed in a small space for transportation, the preferred detail construction being as follows:

The base 2 of the showcase is depressed at the front and ends to receive lower frame pieces 30 screwed to the base and having the upper sides longitudinally grooved or stepped 75 to form inner and outer shoulders 31 and 32 respectively, the adjacent ends of the front and end frame pieces being spaced from each other to accommodate front corner posts 33, the opposite sides of each of which 80 are longitudinally grooved to form inner and outer shoulders 34 and 35 respectively, corresponding to and continuing upwardly from the shoulders 31 and 32. The spaced ends of the lower frame pieces are transversely grooved to form stepped projections 36 fitting snugly into the grooves of the front corner posts and interlocking the members. The lower ends of the front corner posts are each reduced to form a shoulder 37 and a downwardly extending projection 38, the shoulders resting upon the base and the projections being set flush with the edges of the base in front corner notches 39 and held in place by screws. 95

The rear corners of the base are notched at 40 to accommodate the lower reduced ends of the rear corner posts 41 which are flush with the edges of the base and screwed thereto, the inner side of each of such 100 rear corner posts being longitudinally recessed at 42 to receive the edges of the doors 6 and form a tight closure thereby. The front side of each rear corner post is longitudinally grooved or stepped to form inner 105 and outer shoulders 43 and 44 respectively, corresponding to and extending upwardly from the shoulders of the lower end frame pieces, each of which latter abuts against its respective rear corner post and has inner 110 and outer extensions 45 and 46 respectively, which straddle the lower end of the post, the outer extension 46 abutting against shoulder 44 and the inner extension being located in a transverse recess 47 in the inner side of 115 the post and secured by screws to the latter.

The top frame has an inwardly projecting ledge 48 upon which the inner sheet 9 of the top glass double wall rests and is held in place by beading 50, the outer sheet 10 resting upon the upper side of the top frame and being held in place by a removable strip 51 screwed to the rear piece 52 of the frame and having an undercut portion for the reception of the rear edge of sheet 10 which 125 latter and sheet 9 can thus be readily removed from the outside merely by loosening strip 51 and beading 50.

The top frame includes front and end pieces 4, the lower sides of which are long- 130

- tudinally grooved or stepped to form shoulders 53 and 54, respectively which form continuations of shoulders 34, 35, 43, 44 and with the latter and shoulders 31 and 32 receive and support the glass sheets 7 and 8 which latter are held in place by beading 55 upon the outside of the respective sheets so that when occasion arises said sheets can be readily removed from the outside.
- 10 The adjacent end of the front and end pieces 4 of the top frame are mitered and secured together by screws, the outer corners so formed resting upon and being screwed to the front corner posts which are 15 inwardly stepped as at 56 to accommodate the shoulders 53 and 54.

The underside of the rear piece 52 of the top frame is longitudinally recessed at 57 to loosely receive and guide the tops of certain of the doors 6, the others being guided by a retaining strip 58 screwed to the back of the rear piece 52.

The opposite ends of the rear piece 52 rest upon the rear corner posts and are each 25 undercut to form a shoulder 57^a abutting against the inner side of the adjacent post, the upper side of the ends of the rear piece being depressed at 58^a to receive the projecting ends 59 of the end pieces 4 of the top 30 frame which are undercut to form shoulders 60 and 61 respectively abutting against the rear piece 52 and rear corner posts 41, the several members so interlocked being secured by screws which extend down through 35 the frame pieces 52 and 4 into the corner posts.

Owing to the overlapping or interlocking joints a showcase of the above description is particularly suited to act as a receptacle for 40 the preservation of perishable commodities and in view of the facility with which the parts of said case can be disconnected, it can be readily taken apart and compactly packed for transportation and again assembled with a minimum amount of labor.

What I claim is as follows:

1. A case for the reception and preservation by cooling of perishable commodities having spaced inner and outer wall members 50 at the ends, front and top, doors at the back, a two-way ventilating duct leading from the rear of the interior of the case and space between the top wall members and three-way ventilating ducts respectively leading 55 from the front and ends of the interior of the case and the spaces between the end, front and top wall members respectively, all of said ducts being permanently open to the exterior of the case.
2. A case for the reception and preservation by cooling of perishable commodities having a base, corner posts, a top frame upon the corner posts, inner and outer side wall members spaced from each other and 60 extending between the base, corner posts and top frame and inner and outer top wall members supported upon the top frame, such top frame having a duct extending outwardly from the space between the top wall members and ducts extending upwardly 70 respectively from the space between the side wall members and the interior of the case, such upwardly extending ducts joining the outwardly extending duct between the ends of the latter and all of said ducts being permanently open to the exterior of the case. 75
3. In a case for the reception and preservation by cooling of perishable commodities, a base having an opening therein adapted to be brought into communication with the 80 outside atmosphere, corner posts, a top frame upon the corner posts, end, front and top walls, doors for closing the rear of the case, pairs of front and rear uprights spaced longitudinally of the case and disposed at 85 each side of the opening in the base, braces extending between the front and rear uprights at the bottom and having vents therethrough, supports carried by said uprights and the corner posts, shelves adapted to rest 90 upon said supports and an ice chest removably disposed between said pairs of uprights and a perforated cover for said ice chest, said cover being adapted to rest upon the braces when the ice chest is removed. 95
4. In a case for the reception and preservation by cooling of perishable commodities, a base, lower frame pieces extending around the front and end sides of the base and presenting inner and outer shoulders; corner 100 posts presenting inner and outer shoulders continuing upwardly from the shoulders of the lower frame pieces; top frame pieces supported upon the corner posts and presenting shoulders continuing from the shoulders of the corner posts, such top frame also presenting an interior ledge; inner and outer sheets of glass respectively resting upon said inner and outer shoulders and inclosing the case at the front and ends; an inner sheet of glass upon said ledge of the top frame and an outer sheet of glass upon the top frame and closing the case at the top; and sliding doors closing the case at the back, the front of said top frame having 110 three-way ducts therein leading from the interior of the case and from the space between the top sheets and the space between the front sheets, the ends of said top frame having three-way ducts therein leading 115 from the interior of the case and from the space between the top sheets and from the space between the end sheets and the rear of the top frame having two-way ducts therein leading from the interior of the case and from the space between the top sheets. 120
5. In a case for the reception and preservation, by cooling, of perishable commodities, a base having notches at the corners, front and rear corner posts, downwardly ex- 125 65 extending between the base, corner posts and

- tending projections upon said posts and located in said notches, the opposite sides of the front corner posts being longitudinally grooved to present inner and outer shoulders and front and end lower frame pieces upon the base and between and abutting against said posts, the ends of the frame pieces abutting against the front posts being vertically grooved or stepped to fit about 5 the shoulders of said front posts.
6. In a case for the reception and preservation, by cooling, of perishable commodities, a base having notches at the corners, front and rear corner posts, downwardly 10 extending projections upon said posts and located in said notches, the front sides of the rear corner posts being longitudinally grooved to present inner and outer shoulders and lower end frame pieces upon the base 15 and abutting against the rear posts, the inner face of each corner post being transversely recessed and the end of each frame piece abutting against the post having inner and outer projections and straddling the 20 post, the inner projection being located in said recess and the outer projection being disposed against the outer shoulder of the 25 post.
7. In a case for the reception and preservation by cooling of perishable commodities, a base having an opening therein adapted to be brought into communication with the outside atmosphere, corner posts, a top 30 frame upon the corner posts, end, front, and top walls, doors for closing the rear of the case, pairs of front and rear uprights 35 and top walls, doors for closing the rear of the case, pairs of front and rear uprights
- spaced longitudinally of the case and disposed at each side of the opening in the base, braces extending between the front and rear uprights at the bottom and having vents 40 therethrough, supports carried by said uprights and the corner posts, shelves adapted to rest upon said supports and an ice chest, removably disposed between said pairs of uprights and resting on shoulders formed 45 by said braces.
8. In a case for the reception and preservation by cooling of perishable commodities, a base having an opening therein adapted to be brought into communication with the outside atmosphere, corner posts, a top frame upon the corner posts, end, front, and top walls, doors for closing the rear of the case, pairs of front and rear uprights 50 spaced longitudinally of the case and disposed at each side of the opening in the base, braces extending between the front and rear uprights at the bottom and having vents 55 therethrough, supports carried by said uprights and the corner posts, shelves adapted to rest upon said supports and being spaced from the end and front walls and an ice chest removably disposed between said pairs of uprights and resting 60 on shoulders formed by said braces. 65

In testimony whereof, I have signed my name to this specification, in the presence of two subscribing witnesses.

ADELARD AMYOT.
